DESIGN FOR A BATTERY

Clifford Brooks Stevens, Milwaukee, Wis., assignor to Solar Corporation, Milwaukee, Wis., a corporation of Delaware

Application July 9, 1945, Serial No. 120,574

Term of patent 14 years

(Cl. D26—6)

To all whom it may concern:

Be it known that I, Clifford Brooks Stevens, a citizen of the United States, residing at Milwaukee, in the county of Milwaukee and State of Wisconsin, have invented a new, original, and ornamental Design for a Battery, of which the following is a specification, reference being had to the accompanying drawings, forming a part thereof, in which

Figure 1 is a perspective view of a battery showing my new design.

Figure 2 is a perspective view thereof from the side and end opposite that shown in Figure 1.

I claim:

The ornamental design for a battery, as shown.

CLIFFORD BROOKS STEVENS.
